UNITED STATES PATENT OFFICE

ALBERT GOLETZ, OF CRESCENT, OHIO, ASSIGNOR TO PHILLIPS MINE AND MILL SUPPLY COMPANY, OF PITTSBURGH, PENNSYLVANIA, A CORPORATION OF PENNSYLVANIA

DRAWBAR CONSTRUCTION FOR MINE CARS AND THE LIKE

Application filed December 23, 1929. Serial No. 415,935.

This invention relates to mine cars and cars of similar construction, and more particularly to an improved drawbar for cars of this type. The term "mine car" as hereinafter used shall be intended to include cars of this general type whether used for mines or other purposes.

In cars of this type it is the usual practice to provide a continuous drawbar member extending from one end of the car to the other and projecting beyond each end, this drawbar member terminating within the bumper provided at each end of the car. A separate auxiliary drawbar is generally attached to each end of the continuous drawbar and has its outer end positioned above the outer end of the continuous drawbar. A pin is passed through an eye in the auxiliary drawbar, through a link positioned between the auxiliary drawbar and the continuous drawbar, and then through the continuous drawbar. In use, when the cars are jammed together this link prys the upper or auxiliary drawbar member up, deforming it, requiring that it be removed from the car and straightened. As heretofore generally constructed, the auxiliary or upper drawbar member has been permanently riveted to the continuous drawbar member, and in order to remove the auxiliary drawbar member it has been necessary to cut away a portion of the floor of the car, cut off the rivet heads, and then remove the auxiliary drawbar.

After the auxiliary drawbar has been straightened, or where it is necessary to replace one with a new one, it is inconvenient to again rivet the auxiliary drawbar to the continuous drawbar. It has been proposed to use bolts and nuts in place of rivets, but where this has been done and a pulling strain has been put on the drawbar, the nuts have worked loose on the bolts, and the auxiliary drawbar eventually mutilates the bolts, or cuts them off.

According to the present invention there is provided a construction by means of which the pulling strain is transmitted through rivets or the like, but wherein it is possible to remove the auxiliary drawbar and replace it very quickly and easily and without

cutting away any portion of the bottom of the car.

The invention may be readily understood by reference to the accompanying drawing in which

Figure 1 shows one form of main car with a drawbar construction made in accordance with my invention;

Figure 2 is a longitudinal detail view through one end of the drawbar assembly, the view being on a larger scale than Fig. 1;

Figure 3 is a top plan view of the auxiliary drawbar member; and

Figure 4 is a perspective view of the rivet or key from which the strain from the auxiliary member is transmitted to the drawbar member.

In the drawing 2 designates a mine car of any usual or preferred construction having the customary running gear 3 and having a bottom 4. Extending along the bottom inside the car is a continuous drawbar member 5, the outer end portions 6 of which project beyond the ends of the car and extend under the customary bumpers 7 which fits slidably over the end of the sill or bottom 4. Applied to each end of the continuous drawbar member is an auxiliary drawbar member 8 having an inner portion 8^a which rests on top of the continuous drawbar, and an outer terminal portion 8^b which is spaced above the bumper 7. Passing through the terminal portion 8^b and through the end portion 6 of the continuous drawbar member is a coupling pin 9. This coupling pin is adapted to pass through a coupling link indicated in chain lines at 10.

In the particular form of the invention shown, the inner portion 8^a of the auxiliary drawbar member 8 is provided with a longitudinally extending slot 11 and with suitably spaced openings 12. Passing through the openings 12 are bolts 13 having nuts on their lower ends below the car floor, as illustrated, these nuts being readily accessible. Rigidly carried on the continuous drawbar member is an abutment or key 14. In the preferred form of my invention this key 14 is of the type shown in Fig. 4 having two extensions 14^a thereon which pass through the continuous drawbar member 5 and are riveted over

on the underside of the continuous drawbar. The key 14 is of such length that it fits in the slot 11 in the auxiliary drawbar 8.

In this arrangement the bolts 13 merely serve to hold the auxiliary drawbar clamped to or in position on the continuous drawbar 5, while the actual pull or strain is transmitted through the abutment 14. If for any reason it is necessary to remove or replace the auxiliary drawbar 8, it is merely necessary to remove the nuts from the bolts 13, after which the auxiliary drawbar can be readily lifted off. The abutment 14 enters the slot 11, but it does not serve in any way to clamp the auxiliary drawbar to the continuous drawbar. However, since the member 14 is riveted or otherwise rigidly carried on the continuous drawbar, there is no opportunity for play to develop even though the nuts on the bolts 13 might work loose, and the strain and pull is always transmitted through the rigid key or abutment 14.

It will be obvious that the key and slot arrangement may be otherwise arranged to secure the same effect, the invention not being confined to the particular arrangement herein specifically described. The invention furthermore permits the holes for the bolts 13 to be relatively large and loose, permitting the easy insertion and removal of these bolts because none of the pull endwise need be transmitted through these bolts. The bumper member 7 which is of channel shape serves to protect the end of the bottom 4 from abrasion and to distribute any impact over the entire surface of the car body covered by the bumper. The bumper also serves the function of preventing the end portions of the main drawbar 5 from being distorted by the various stresses and strains to which it is subjected. In devices of this class hitherto made, the bumper has also served to transmit tension strains either directly to the main drawbar or to the floor member. In this invention, the bumper does not serve any such purpose, nor is there any connection to the main drawbar or to the auxiliary drawbar. Various other changes and modifications may be made within the contemplation of my invention and under the scope of the following claims.

I claim:

1. A mine car comprising a body having a bottom and a main drawbar extending along the bottom inside the car and projecting beyond the opposite ends thereof, a bumper on

each end of the car and slidably embracing the end of the drawbar, an auxiliary drawbar having an upwardly bent outer end portion positioned over the projecting end portion of said main drawbar and having an inner end portion resting on top of the main drawbar inwardly from the bumper, and means spaced inwardly from the bumper connecting the auxiliary drawbar and the main drawbar, said means comprising spaced bolts and nuts passing loosely through the main and auxiliary drawbars and constituting clamping means for the main and auxiliary drawbars, and a cooperating key and slot arrangement in the main and auxiliary drawbars also positioned rearwardly of the bumper for transmitting stresses and strains from the auxiliary to the main drawbar, the relation of the bumper and drawbar being such that impacts on the bumper are not transmitted to the connecting means between the main and auxiliary drawbars.

2. A mine car comprising a body having a bottom and a main drawbar extending along the bottom inside the car and projecting beyond the opposite ends thereof, a bumper on each end of the car and slidably embracing the end of the drawbar, an auxiliary drawbar having an upwardly bent outer end portion positioned over the projecting end portion of said main drawbar and having an inner end portion resting on top of the main drawbar inwardly from the bumper, and means spaced inwardly from the bumper connecting the auxiliary drawbar and the main drawbar, said means comprising spaced bolts and nuts passing loosely through the main and auxiliary drawbars and constituting clamping means for the main and auxiliary drawbars, a key consisting of a body portion having lugs thereon, which lugs pass through openings in the main drawbar and project beyond the projecting portions being upset so as to rivet the key to the main drawbar, a cooperating slot in the auxiliary drawbar, the said key and slot arrangement being positioned rearwardly of the bumper for transmitting stresses and strains from the auxiliary to the main drawbar, the relation of the bumper and drawbar being such that impacts on the bumper are not transmitted to the connecting means between the main and auxiliary drawbars.

In testimony whereof I have hereunto set my hand.

ALBERT GOLETZ.
